ERNEST A. WALKER, OF NEWARK, NEW JERSEY, ASSIGNOR TO DAVID TUNICK, OF NEWARK, NEW JERSEY, AND BENJAMIN M. REZNIK, OF CALDWELL, NEW JERSEY

DESIGN FOR A LIGHTING FIXTURE BODY OR ARTICLE OF ANALOGOUS NATURE

Application filed March 23, 1931. Serial No. 39,213. Term of patent 7 years.

To all whom it may concern:

Be it known that I, ERNEST A. WALKER, a citizen of the United States of America, and a resident of Newark, county of Essex, and State of New Jersey, have invented a new, original, and ornamental Design for a Lighting Fixture Body or Article of Analogous Nature, of which the following is a specification, reference being had to the accompanying drawings, forming a part hereof.

In these drawings:

Figure 1 is a side elevational view of the

lighting fixture body or article of analogous nature; and

Figure 2 is an inverted plan view of the same, the parts shown in outline being ornamented in the same manner as the parts more fully illustrated.

I claim:

The ornamental design for a lighting fixture body or article of analogous nature substantially as shown and described.

ERNEST A. WALKER.
